UNITED STATES PATENT OFFICE.

FREDERICK H. LIVINGSTON, OF BINGHAMTON, NEW YORK, ASSIGNOR TO WILLIAM J. VOGT, OF BINGHAMTON, NEW YORK.

PHONOGRAPH CONSTRUCTION AND HOUSING.

1,424,835.

Specification of Letters Patent. Patented Aug. 8, 1922.

Application filed June 9, 1920. Serial No. 387,709.

To all whom it may concern:

Be it known that I, FREDERICK H. LIVINGSTON, a citizen of the United States, residing at Binghamton, in the county of 5 Broome and State of New York, have invented certain new and useful Improvements in Phonograph Constructions and Housings, of which the following is a specification.

10 This invention has reference generally to improvements in that class of inventions known as musical instruments and more particularly relates to an improved phonograph.

15 It is the primary aim and object of this invention to provide a device of the above mentioned character wherein the housing for the machine and its horn is of a novel construction, being in the shape of a table 20 which when the machine is not in use may be used in the capacity of an ordinary library table, while when it is desired to use the phonograph a drawer containing the main operating parts of the phonograph 25 may be extended so that a record may be played when on the revolving disk while the drawer is in either an opened or closed position.

As an equally important object this invention 30 embraces the provision of a device of the above mentioned character wherein an improved adjustable sound passage is provided between the drawer and the horn to insure of the proper operation of the phonograph as well as a means for modifying the tone thereof.

More particularly this invention consists 35 of a device of the above character wherein the horn is rigidly mounted in a compartment in the table and communicates with the sound passage, also formed beneath the top of the table, improved means being provided for maintaining constant communication between the sound box which is carried 45 by the drawer and the sound passage to conduct sound variations regardless of the position of the drawer.

More specific objects of the invention may 50 be said to consist of the provision of improved means for mounting the drawer; the construction of a partition forming a part of the sound passage or conduit, and the construction of the sound passage.

Other objects as well as the nature, characteristic features and scope of this inven-

tion will be more readily apparent from the following description taken in connection with the accompanying drawings and pointed out in the claims, forming a part of this specification.

60 The invention is clearly illustrated in the accompanying drawings, in which:—

Fig. 1 is a side elevational view of one form of the invention.

Fig. 2 is a similar view of a slightly modified form of the device.

Fig. 3 is an end elevation of the form shown in Fig. 1.

Fig. 4 is a horizontal sectional view taken on the line 4—4 of Fig. 2.

70 Fig. 5 is an end elevation of the form shown in Fig. 2.

Fig. 6 is an enlarged sectional detail showing the means for locking one of the doors.

Fig. 7 is an enlarged sectional view taken 75 on the line 7—7 of Fig. 4, showing the sound passage or conduit in section, the drawer containing the machine parts in elevation and the horn in dotted lines.

Fig. 8 is a horizontal sectional view taken 80 on the line 8—8 of Fig. 1.

Fig. 9 is a side elevational detail of the drawer, of the form shown in Fig. 8, removed.

Fig. 10 is side elevation of the plate partition forming a part of the modification of 85 Fig. 8.

Fig. 11 is a side elevational detail looking toward the inner face of a part of the front wall of the body of the table, showing a 90 part of the means for mounting the drawer.

Fig. 12 is top plan detail, partly in section, of the horn, drawer and passage of the arrangement shown in Fig. 8, and

Fig. 13 is an enlarged fragmentary longitudinal sectional detail view on the line 95 13—13 of Fig. 8.

Similar characters of reference are employed in all of the above described views to indicate corresponding parts.

100 Referring now, more particularly, to the accompanying drawings, especially Figs. 1, 3 and 8 to 13, there is provided a housing preferably in the form of a table A comprising a top (a) and supporting legs for 105 the main body portion. One end of the body portion contains a drawer B for records, etc., while the compartment adjacent thereto accommodates the horn C of the phonograph, the horn compartment being covered 110

at its open end by a fret-worked screen (d), which is removably positioned medially of the front side of the body portion for ornamental purposes. Immediately to the right 5 of the horn compartment and opening at the adjacent end of the body is a compartment for the drawer D which contains the main working parts of the phonograph. The drawer is provided with a removable 10 lid or cover E on which is mounted the revolving disk 2 and the tone arm 3, which carries the sound reproducer 4. The drawer is also divided into a large compartment 5 which receives the operating mechanism for 15 the disk and a small compartment 6 positioned at the inner right hand corner of the drawer and directly beneath and communicating with the tone arm 3, this compartment being provided in its outer side 20 with a sound opening 7 for a purpose to appear.

Mounted longitudinally within the body portion of the table and spaced in parallel relation to the rear wall thereof and in juxtaposed relation to the right side of the drawer D is the improved plate partition 8. At the inner end of partition 8, there is a vertical partition 9 which when taken with upper and lower partitions 10, the rear wall of 25 the table and the partition 8 forms a sound passage 11 extending horizontally along the inner face of the rear side of the table and thence on an incline to a point opposite the inner end of the horn C to which communication is established by means of an opening 12. Continuous communication between the opening 7 and the passage 11 is effected by means of a horizontal slot 13 provided in the partition 8. Mounted transversely 30 through the right side of the drawer and adjacent the partition forming the compartment 6 is a plate 15 which operates through the slot (13) and extends across the passage or conduit (11) being adapted to move 35 horizontally through the slot simultaneously with corresponding movements of the drawer (D), effecting a closure for the outer part of the passage (11) for the purpose of lengthening or shortening the said passage 40 according to the position of the drawer (D).

With a view toward providing improved means for slidably mounting the drawer (D), a drawer slide (14) is mounted on the side of the plate partition (8) to support 45 the right side of the drawer while the outer surface of the opposite side of the drawer is supported on drawer slides (16 and 17), the latter being movably laterally on bolts (18) about which are arranged coiled springs 50 (19), the ends bearing against the slides (16 and 17) of the adjacent body wall so that the slides will act to yieldingly hold the drawer against the partition (8) in addition to permitting a relative sliding movement between the drawer and the partition. 55

Mounted above the drawer D in the end wall of the body portion by means of hinges 20 is a door F and in effecting a removable engagement of the door there is mounted for vertical movement in the upper edge thereof 70 a spring pressed round headed bolt 21 which engages the slotted keeper plate 22 carried by the under surface of the table top (a).

In order to effect an opening of the door simultaneously with the opening of the 75 drawer there is mounted on the upper edge of the drawer, a lug 23 (shown in Fig. 13) adapted for contact with the inner face of the door near the lower edge thereof.

Through the front of drawer D there is 80 mounted the usual operating handle of the phonograph, while on the upper edge of the drawer near the front there is arranged a slotted plate 25 through which projects the disk control lever 26.

In Figs. 2 and 4 to 7, inclusive, there is 85 shown a slightly modified arrangement. In this form of the invention the construction of the horn and passage is varied to the extent that the passage 11' in reality constitutes an angular branch of the inner end of the horn C', being provided on its side adjacent the drawer D' with a slot 13' which receives the plate 15' carried by the drawer. The remaining parts are substantially the 90 same as shown in the other form with the reference characters primed.

In using the instrument it is apparent 95 that it is only necessary to open the drawer D which simultaneously opens the door F 100 and during the outward sliding movement of the drawer the plate 15 will slide through the slot 13 and the passage 11 forming a closure for the outer end of the passage and at the point immediately adjacent the opening 7. When a record is placed on disk 2 and the machine started in the usual manner the sound travels through the tone arm into the compartment 6 thence through the opening 7 and slot 13 to the passage 11 and 105 finally out through the horn C. By this arrangement it will of course be apparent that the tone will be modified according to the position of the drawer D, by reason of the provision of the continuous communication 110 between opening 7 and the sound passage 11.

It is believed in view of the foregoing 115 that a further detailed description of the operation of the invention will be unnecessary. Likewise it is believed that the advantages of the invention will be readily apparent.

Having thus fully described the invention, what is claimed as new and desired to be secured by Letters Patent is:—

1. In a musical instrument, a housing, a horn rigidly mounted therein, a drawer slidably mounted in the housing and provided with a partition forming two compartments, phonograph operating mechanism mounted 120 125 130

in one of the compartments of the drawer, 5
a tone arm arranged in communication with
the other compartment and carried by the
drawer and an adjustable passage establish-
ing communication between the horn and
the compartment which communicates with
the tone arm, substantially as described.

2. A device as claimed in claim 1 wherein
the compartment in the drawer which com- 10
municates with the tone arm is provided
with an opening and wherein the passage is
provided with a horizontal slot registerable
with the opening regardless of the position
of the drawer, and a plate carried by the

drawer adjacent the opening and operating 15
through the slot and the passage and form-
ing a closure for the outer end of the pas-
sage.

3. In a device of the character described
the combination with a stationary horn and 20
a sliding drawer containing the operating
parts of a phonograph mechanism, of an ad-
justable sound passage between the drawer
and the horn through which sound waves are
conducted.

In testimony whereof I have affixed my
signature.

FREDERICK H. LIVINGSTON.
